UNITED STATES PATENT OFFICE

ARVEL M. BALCH, OF LOS ANGELES, CALIFORNIA

AIRSHIP

Application filed February 15, 1929, Serial No. 340,120. Renewed September 18, 1930.

The present invention relates generally to aircraft and has for its prime object to combine the features of heavier than air and lighter than air craft. This object is carried out by an exceedingly simple construction which is strong and durable, and thoroughly efficient and reliable in use, maneuverability, stability and operation.

Another very important object of the invention resides in the provision of an aircraft of this nature wherein gas tanks or bags may be mounted along the sides thereof and along the top thereof in a compact and convenient manner to enhance the maneuverability and stability of the craft.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the air craft embodying the features of this invention showing an intermediate portion broken away and in section,

Figure 2 is a top plan view thereof,

Figure 3 is a transverse vertical section taken substantially on the line 3-3 of Figure 1,

Figure 4 is a fragmentary longitudinal vertical section taken substantially on the line 4-4 of Figure 3,

Figure 5 is a horizontal fragmentary longitudinal section taken substantially on the line 5-5 of Figure 1,

Figure 6 is a perspective view of one of the gas tanks or bags, and

Figure 7 is an enlarged detail section taken substantially on the line 7-7 of Figure 6.

Referring to the drawing in detail, it will be seen that the numeral 5 denotes a stream line fuselage having extending from the forward portion of its sides wings 6 and from adjacent its tail portion wings 7. The wings 6 and 7 are provided with ailerons 8 and 9 respectively. A rudder 10 is mounted to the rear end of the fuselage.

This fuselage has a body constructed of skeleton work 15 covered by fabric F or any

other suitable material such as duralumin for example. A central passenger and storage compartment 16 is formed in the fuselage having side walls 17 to provide side spaces 18 in which are mounted gas containers 19 in the form of bags or tanks and separated from each other by suitable bracing work 20.

Each container 19 is provided with a check valve inlet 21 with a screw plug closure 22 associated therewith. These containers may be readily filled with helium, hydrogen, or other like gas. In the top of the fuselage there is an upper compartment 25 in which is housed gas containers 26 and below this compartment 25 one to each side thereof are air passages 27 and to the sides of air passages 27 are other air passages 28 which merge together toward the tail as is indicated to advantage in Figure 5.

Suitable skeleton work 29 is provided to support the necessary partitions for forming these passages. Air escapes 30 are provided in the top of the compartment 16 so that air may be sucked from this compartment and keep the same properly ventilated.

Below the compartments 16 and 18 is a compartment 31 braced by skeleton work 32 and this may be used as a storage place for fuel or for gas bags if so desired. An engine 33 is mounted in front or at the nose of the fuselage for operating the propeller 34. A running gear 35 is provided below the front of the fuselage and a tail skid 36 is provided below the rear portion of the fuselage so that the air craft may land safely.

From the above detailed description it will be seen that I have devised aircraft embodying the features of lighter than air and heavier than air craft wherein the parts are so distributed and arranged as to afford advantages of stability and maneuverability without sacrificing strength or durability.

The air passages form means for properly ventilating the compartment and minimize resistance allowing the air thrown back by the propeller to escape rearwardly and form a column of air through the fuselage with gas sustaining means above and below and to the sides of this column of air so as to gain great stability in storms and under other try-

ing conditions. Furthermore it will be seen that I have devised an aircraft which will float on water.

Thus the air craft is adapted for long flights since it may land under most any conditions even though it should give out of fuel. It will also be seen that this aircraft is capable of proper maneuvering under the most trying of conditions in storms and the like.

10 It is though that the construction, utility and advantages of this invention will now be quite apparent to those skilled in this art without a more detailed description thereof.

15 The present embodiment of the invention has been disclosed in considerable detail merely for the purposes of exemplification since in actual practice it attains the features of advantage enumerated as desirable in the statement of the invention and the above description.

20 It will be apparent that changes in the details of construction, and in the combination and arrangement of parts may be resorted to without departing from the spirit or scope of 25 the invention as hereinafter claimed or sacrificing any of its advantages.

Having thus described my invention, what I claim as new is:

1. In an aircraft of the class described, 30 a fuselage, lighter than air lift means to the sides of the fuselage, lighter than air lift means along the top of the fuselage, air passages among the lighter than air lift means and formed through the fuselage longitudinally, said fuselage being formed with a passage compartment between the sides of the 35 lighter than air lift means and below the air passages, and means communicating the top of the passage or compartment with the air 40 passages to provide for proper circulation of air.

2. In an aircraft of the class described, a fuselage, lighter than air lift means to the sides of the fuselage, lighter than air lift means along the top of the fuselage, air passages among the lighter than air lift means and formed through the fuselage longitudinally, said fuselage being formed with a passage compartment between the sides of the 45 lighter than air lift means and below the air 50 passages, and means communicating the top of the passage or compartment with the air passages to provide for proper circulation of air, said fuselage being formed with a closed 55 compartment at the bottom thereof.

3. In an air craft of the class described, a fuselage, lighter than air lift means to the sides of the fuselage, lighter than air lift means along the top of the fuselage, air 60 passages among the lighter than air lift means and formed through the fuselage longitudinally, said fuselage being formed with a passage 65 compartment between the sides of the lighter than air lift means and below the air 70 passages, and means communicating the top of the passage or compartment with the air 75 passages to provide for proper circulation of air, said fuselage being formed with a closed 80 compartment at the bottom thereof, wings 85 extending outwardly from forward portions of the air craft, ailerons associated with the wings, wings extending outwardly from the sides to the rear portions of the fuselage, ailerons associated with the rear 90 wings.

4. In an air craft of the class described, a fuselage, lighter than air lift means to the sides of the fuselage, lighter than air lift means along the top of the fuselage, air 95 passages among the lighter than air lift means and formed through the fuselage longitudinally, said fuselage being formed with a passage compartment between the sides of the 100 lighter than air lift means and below the air 105 passages, and means communicating the top of the passage or compartment with the air 110 passages to provide for proper circulation of air, said fuselage being formed with a closed compartment at the bottom thereof, wings 115 extending outwardly from forward portions of the air craft, ailerons associated with the wings, wings extending outwardly from the sides to the rear portions of the fuselage, ailerons associated with the rear 120 wings.

5. In an air craft of the class described, a fuselage, lighter than air lift means to the sides of the fuselage, lighter than air lift means along the top of the fuselage, air 125 passages among the lighter than air lift means and formed through the fuselage longitudinally, said fuselage being formed with a passage compartment between the sides of the 130 lighter than air lift means and below the air 135 passages, and means communicating the top of the passage or compartment with the air 140 passages to provide for proper circulation of air, said fuselage being formed with a closed compartment at the bottom thereof, wings 145 extending outwardly from forward portions of the air craft, ailerons associated with the wings, wings extending outwardly from the sides to the rear portions of the fuselage, ailerons associated with the rear 150 wings.

6. In an aircraft of the class described, a fuselage, lighter than air lift means to the sides of the fuselage, lighter than air lift means along the top of the fuselage, air 155 passages among the lighter than air lift means and formed through the fuselage longitudinally, said fuselage being formed with a passage compartment between the sides of the 160 lighter than air lift means and below the air 165 passages, and means communicating the top of the passage or compartment with the air 170 passages to provide for proper circulation of air, said fuselage being formed with a closed 175 compartment at the bottom thereof, wings 180 extending outwardly from forward portions of the air craft, ailerons associated with the wings, wings extending outwardly from the sides to the rear portions of the fuselage, ailerons associated with the rear 185 wings.

ailerons associated with the wings, a rudder mounted at the tail of the fuselage, said side lighter than air lift means including a plurality of tanks.

- 5 7. In an air craft of the class described, a fuselage, lighter than air lift means to the sides of the fuselage, lighter than air lift means along the top of the fuselage, air passages among the lighter than air lift means
10 and formed through the fuselage longitudinally, said fuselage being formed with a passage compartment between the sides of the lighter than air lift means and below the air passages, and means communicating the top
15 of the passage or compartment with the air passages to provide for proper circulation of air, said fuselage being formed with a closed compartment at the bottom thereof, wings extending outwardly from forward portions
20 of the air craft, ailerons associated with the wings, wings extending outwardly from the sides to the rear portions of the fuselage, ailerons associated with the wings, a rudder mounted at the tail of the fuselage, said side
25 lighter than air lift means including a plurality of tanks, each tank including a check valved inlet, and a screw threaded plug for closing the same.

In testimony whereof I affix my signature.

30 ARVEL M. BALCH.
